UNITED STATES PATENT OFFICE.

JOHN L. GRISWOLD, OF DODGE CENTER, MINNESOTA.

PIG-GUARD.

1,211,839.

Specification of Letters Patent.

Patented Jan. 9, 1917.

Application filed March 27, 1916. Serial No. 87,056.

To all whom it may concern:

Be it known that I, JOHN L. GRISWOLD, a citizen of the United States, residing at Dodge Center, in the county of Dodge and 5 State of Minnesota, have invented certain new and useful Improvements in Pig-Guards; and I do hereby declare the following to be a full, clear, and exact description of the invention, such as will enable others 10 skilled in the art to which it appertains to make and use the same.

My invention relates to improvements in pig guards; and, to this end, the invention 15 consists of the novel devices and combinations of devices hereinafter described and defined in the claims.

In the accompanying drawings, which 20 illustrate the invention, like characters indicate like parts throughout the several views.

Referring to the drawings, Figure 1 is a view, partly in elevation and partly in section, with some parts illustrated diagrammatically, and some parts shown in different 25 positions, by means of broken lines; Fig. 2 is a front elevation of the improved guard, some parts being broken away; Fig. 3 is a fragmentary detail view, with some parts sectioned on the line $x^3 x^8$ of Fig. 2, on an 30 enlarged scale; and Fig. 4 is a perspective view of one of the wall brackets on an enlarged scale.

The numerals 1 and 2 indicate, respectively, one of the walls and the floor of a 35 hog house. As shown, the pig guard is in the form of a horizontal tubular rail 3, normally held by a pair of arms 4 spaced outward of the front 1 and above the floor 2. The arms 4 are secured, at one of their 40 ends, to the wall 1 by a pair of wall brackets 5 and have, at their other or free ends, integrally formed hubs 6 through which are telescoped the guard rails 3. Set screws 7 hold the guard rail 3 and the hub 6 against 45 both rotary and endwise movement.

The wall brackets 5 are L-shape in cross section and in each flange thereof are countersunk holes through which screws 50 may be passed for securing said brackets either to the side or end walls of the hog house. Projecting from one of the flanges of each wall bracket 5, is a pivot stud 8 and projecting from the other flange thereof, is a lug 9. These lugs 9 extend transversely of the studs 8 and are located outward therefrom, as best shown in Fig. 4.

The opposite ends of the arms 4, from the guard rail 3, are provided with longitudinally extended slots 10, through which the studs 8 project and connect said arms to the wall brackets 5, with freedom for vertically swinging movement and limited endwise movement. In applying or removing the arms 4 from the wall brackets 5, the same must be held in substantially horizontal position, to clear the lugs 9 and give them a lateral movement to carry the studs 8 into or out of the slots 10, depending on whether or not the arms 4 are being applied to or removed from the brackets 5.

Integrally formed with each arm 4, is a stop finger 11 which engages the wall 1 and holds the respective arm 4 obliquely outward therefrom. In swinging the arms 4 from the full line to the dotted line position, 75 as shown in Fig. 1, the slot and pin connections 8 and 10 permit a slight endwise movement of said arms. This movement of the arms 4 carries their pivoted ends a sufficient distance below the studs 8 to prevent pivotal 80 movement thereof by the engagement of the arms 4 with the wall brackets 5.

The wall brackets 5 are so located as to support the guard rail 3 a sufficient distance above the floor 2 to permit the little pigs to 85 pass thereunder, but not the large or full grown ones. The stop fingers 11 hold the guard rail 3 outward from the wall 1 a distance sufficient to permit the little pigs to lie on the floor between the guard rail 3 and wall 1, or to freely move about therebetween. Obviously, the guard rail 3 prevents the large or full grown pigs from lying on the little ones, crowding the same against the wall or otherwise hurting the 95 same.

When cleaning out the hog house, the improved guard may be raised, so as to be out of the way, as indicated by broken lines in Fig. 1.

It is, of course, understood that the improved pig-guard may be applied to a partition or fence dividing a hog house into pens, as well as to the walls thereof. These partitions are usually removably mounted 105 or hinged, in order to permit the same to be swung out of the way. One of the purposes of detachably connecting the arms 4 to the brackets 5 is to permit the same, when supported from a partition, to be removed 110 when said partition is turned or moved into an inoperative position.

What I claim is:—

1. The combination with the wall and floor of a hog house, of a pair of arms secured to the wall, and a guard rail carried by the arms and gravitationally held thereby spaced outward from the wall and above the floor with freedom for raising movement.
  2. The combination with the wall and floor of a hog house, of a pair of arms secured to the wall, a guard rail carried by the arms and held thereby above the floor, and a stop finger on each of said arms directly and loosely engaging the wall, for holding the guard rail spaced apart therefrom.
  3. The combination with the wall and floor of a hog house, of a pair of brackets secured to the wall, a pair of arms pivoted to the bracket for vertical swinging movement, a guard rail carried at the free ends of the arms and held thereby above the floor, a stop finger on each of the arms loosely engaging the wall for holding the guard rail spaced apart therefrom, and means for holding the arms raised.
  4. The combination with the wall and floor of a hog house, of a pair of brackets secured to the wall, a pair of arms slot and pin connections secured to the brackets by slot and pin connections, a guard rail carried at the free ends of the arms and held thereby above the floor, a stop finger in each of the arms engageable with the wall for holding the guard rail spaced apart therefrom, said arms arranged, when raised, to interlock with the brackets by an endwise sliding movement.
  5. The combination with the wall and floor of a hog house, of a pair of brackets secured to the wall, a pair of arms, slot and pin connections securing the inner ends of the arms to the brackets for vertical swinging movement, and a guard rail on the outer end of the arms and supported in an operative position thereby above the floor, said arms when raised having a limited endwise movement on their slot and pin connections to engage the brackets as stops for holding the guard rail in an operative position.
- In testimony whereof I affix my signature in presence of two witnesses.

JOHN L. GRISWOLD.
